UNITED STATES PATENT OFFICE.

ERIC C. MOORE, OF ROCHESTER, NEW YORK, ASSIGNOR TO KALAMAZOO LOOSE LEAF BINDER CO., OF KALAMAZOO, MICHIGAN, A CORPORATION.

LOOSE-LEAF BINDER.

1,410,707.

Specification of Letters Patent. Patented Mar. 28, 1922.

Application filed March 19, 1920. Serial No. 367,148.

To all whom it may concern:

Be it known that I, ERIC C. MOORE, of Rochester, in the county of Monroe and State of New York, have invented certain new and 5 useful Improvements in Loose-Leaf Binders; and I do hereby declare the following to be a full, clear, and exact description of the same, reference being had to the accompanying drawings, forming a part of this specification, and to the reference-numerals 10 marked thereon.

My present invention relates to stationery and more particularly to loose leaf binders embodying covers or holding members and separate perforated leaves secured therein by impaling posts from which they may be detached at will and the invention has for its object to provide a binder of this 15 nature in which certain of the impaling devices characterized as "transfer members," may be removed with or without leaves that it may be desired to transfer with them, from either side of the binder, that is, by lifting either cover. To these and other ends 20 the invention resides in certain improvements and combinations of parts all as will be hereinafter more fully described, the novel features being pointed out in the claims at the end of the specification.

30 In the drawings:

Figure 1 is an end view of a closed binder constructed in accordance with and illustrating one embodiment of my invention;

Figure 2 is an enlarged fragmentary sectional view taken transversely through the same near its center, with the leaves removed;

Figure 3 is an enlarged longitudinal sectional view taken substantially on the line 40 3—3 of Figure 2;

Figure 4 is a detail side view of one of the transfer members, and

Figure 5 is a fragmentary plan view of one of the leaves and adjacent impaling devices of the cover;

Similar reference numerals throughout the several views indicate the same parts.

Loose leaf binders of the kind here involved have hitherto been made with two 50 sets of impaling posts, one set permanently secured to one cover member and the other set, in a relatively reverse position, detachably arranged on the other side of the pile

of leaves and just beneath the other cover member. The last mentioned set of impaling posts constitutes a transfer member by means of which any desired number of the leaves may be removed together from the binder while held in register with each other, so that they may be replaced with 60 similar ease but in order to accomplish this removal or replacement, it has been necessary to see that the binder is lying on that cover member which carries the fixed impaling devices and it has been possible to 65 remove only the uppermost leaves or, at least, necessary to remove them first. In the practice of my present invention, it is possible to remove sheets from either side of the pile, selectively, with equal ease. 70

Referring more particularly to the drawings, I have shown my improvements embodied in a familiar type of binder embodying a back A and cover members B and C hinged thereto at D. The cover members 75 each comprise a connecting portion E to which the body of the cover is hinged at F. The hinges F are utilized in the ordinary use of the book to open and close the covers while the leaves are held tightly together and 80 the connecting members E and back A are, for the time, in fixed relationship. The hinges D are utilized only in further opening the binder through the release of locking elements hereinafter described, to make 85 changes in the dispositions of the leaves. Both sets of hinges D and F are preferably constituted by the ornamental leather or similar flexible covering for finishing the parts indicated at G in the sectional views. 90

The connecting members E of the covers are similar in structure so far as the features thereof are concerned and differ in detail only in the location of the sockets for the impaling posts and therefore a description 95 of one will suffice for both. In the construction of each, two inverted sheet metal channel members 1 are reversed with respect to each other and placed with their flanges overlapping to provide a box-like housing and 100 the inner one is provided with spaced apertures 2 and 3 for the impaling posts and the connecting device hereinafter referred to. Slidable longitudinally within the housing and against the said outer channel member 105 thereof to which it is confined by guide pins

4 is a lock or bolt 5 having a projecting operating portion or finger-piece 6 at one end thereof extending to the exterior of the housing. The bolt is perforated or cutaway at 5 the points 7, 8 and 9, corresponding approximately with the sockets 2 and 3 and in connection with the perforation 9, a locking shoulder 10 is formed adjacent the socket 2. A suitable spring 11 connected to the bolt 10 and to the housing, tends to hold the locking shoulder 10 opposite the socket 2 to engage an element occupying the same. The locking shoulder is moved beyond the socket against the tension of the spring 11 by 15 pressing inwardly upon the operating member 6 at the end of the binder. The movement of the bolt under the influence of the spring is limited by the engagement of an abutment 12 thereon with a stop 13 on the 20 housing.

Superposed upon the inner side of each housing and lying flat against the same are two transfer bars 14 and 15 having fixed thereto spaced impaling posts 16 and 17, the 25 respective pairs of posts being so arranged on their carriers that one set fits between the other set, as shown. The loose leaves H fit these impaling posts and are held in register thereby, as shown in Figure 1. The 30 posts extend to the opposite connecting member E from that against which their carrying bar is disposed and occupy the sockets 3 of such opposite member, the perforations 8 in the bolts 5 being designed merely to 35 give them clearance during the movements of the bolts. In the present instance, I have shown fins or ribs 18 on the set of impaling posts 17 which serve to space the transfer bars 14 and 15 apart, but they are primarily 40 for the purposes of another invention best illustrated by Figure 5 and having for its purpose to prevent loose leaves from one book or binder from being applied to another binder in which they do not belong. 45 For instance, in one binder, the irregular or finned posts 17 would be at the ends of the perforations of the leaf 8 and the cylindrical ones 16 in the center, whereas in the other binder, the positions of these pairs 50 would be reversed.

The parts cooperate in this way to form the binder and accommodate the leaves but so far, nothing has been described to bind the cover members and their connecting portions E together and clamp the leaves or retain them against the disengagement of the impaling members 16 and 17 from the covers. The means I employ for this purpose consists, in the present instance, of a separate post 19, not an impaling post, preferably arranged centrally of the row of other posts and of the longitudinal extent of the connecting members, and to accommodate which the leaves 8 are preferably cutaway, 60 as shown at 20 in Figure 5, so that they

clear it at all times. The body of the post 19 may be rectangular in cross section, as in the accompanying illustration, affording shoulders 21 at the ends abutting the transfer bars 14 and 15 to space them independently of the fins 18 before described. Beyond the shoulders, cylindrical tips 22 on the retaining post project into the socket 2 of the connecting members E and are normally locked snugly to the connecting members by the engagement of the shoulders 10 on the bolts 5 with shoulders on the posts formed by notching the tips as shown at 23 in Figure 3. The rounded ends of the tips, when inserted in the sockets, preliminarily 80 displace the locking shoulders, thus rendering the bolt an automatic or spring lock.

The operation and use of the device will be clear from the above description. If it is desired to remove leaves or to open the 85 binder from the top with it disposed as in the figures and the cover B uppermost, the bolt 5 of that cover member is pressed in and the cover thrown back on the hinge D instead of the hinge F. The connecting post 19 is then relieved from the bolt to be drawn from the socket 2 and there is at no time anything to prevent the withdrawal of the connecting member from the ends of the upstanding impaling posts 95 16. The transfer bar 15 with its downwardly extending impaling posts 17 is left lying on the pile of leaves or on the shoulders 21 of the post 19 and is free to be raised from the latter and from the impaling posts 100 16 together with such of the leaves as it is desired to hold on the posts 17 as they are withdrawn upwardly from their free engagement with the lower connecting member E. The connecting post 19 remains in place 105 and to prevent the lower transfer bar 14 from having a tendency to pivot on the connecting post 19 by which it is held, I provide short centering projections 24 thereon that cooperate with apertures or recesses 25 110 in the connecting member. In the present instance, these projections are supplied by shallow rounded extensions on the butt ends of the impaling posts. The parts are returned in reverse order and the cover again 115 locked with the connecting post 19 by simply pressing down on it.

The same method is pursued if the book is to be opened from the other side for the removal of those leaves which, in the prior 120 instance, were the bottom leaves of the pile. The transfer member 15 remains attached as the primary impaling element of the ordinary binder and the transfer bar 14 with the posts 16 is the one that is lifted off with 125 the leaves. In no case is it necessary to remove the connecting or locking post 19.

I claim as my invention:

1. In a loose leaf binder, the combination with cover members of a pair of detachable 130

transfer bars normally lying adjacent to the respective cover members and each having impaling posts thereon adapted to extend through the leaves and means for securing 5 the transfer bars together.

2. In a loose leaf binder, the combination with cover members, of a pair of detachable transfer bars normally lying adjacent to the respective cover members and each having 10 impaling posts thereon adapted to extend through the leaves, and means independent of the impaling posts for securing the transfer bars together.

3. In a loose leaf binder, the combination 15 with cover members, of a pair of detachable transfer bars normally lying adjacent to the respective cover members and each having impaling posts thereon adapted to extend through the leaves, an independently operable lock on each cover member, and means 20 cooperating with said lock for securing the adjacent transfer bar thereto.

4. In a loose leaf binder, the combination 25 with cover members, of a pair of detachable transfer bars normally lying adjacent to the respective cover members and each having impaling posts thereon adapted to extend through the leaves, an independently operable lock on each cover member and means 30 cooperating with both locks for securing the transfer bars to the respective cover members.

5. In a loose leaf binder, the combination 35 with cover members, of a pair of detachable transfer bars normally lying adjacent to the respective cover members and each having impaling posts thereon adapted to extend through the leaves, an independently operable lock on each cover member and means 40 cooperating with both locks for securing the transfer bars to the respective cover members, said means also acting to space the transfer bars from each other.

6. In a loose leaf binder, the combination 45 with cover members having sockets therein, of a pair of detachable perforated transfer bars normally lying adjacent to the respective cover members and each having impaling posts thereon adapted to extend through 50 the leaves, through the perforations of the opposite bar and into the sockets of the opposite cover member, and means for securing the cover members together.

7. In a loose leaf binder, the combination 55 with cover members having sockets therein, of a pair of detachable perforated transfer bars normally lying adjacent to the respective cover members and each having impaling posts thereon adapted to extend through 60 the leaves, through the perforations of the opposite bar and into the sockets of the opposite cover member, and means including independently operable locks on the respective cover members for securing the transfer bars 65 thereto.

8. In a loose leaf binder, the combination with cover members having sockets therein, of a pair of detachable perforated transfer bars normally lying adjacent to the respective cover members and each having impaling posts thereon adapted to extend through the leaves, through the perforations of the opposite bar and into the sockets of the opposite cover member, a separate post also extending through perforations in the transfer bars and into sockets of both cover members and independently operable locks on the respective cover members cooperating with the opposite ends of said separate post.

9. In a loose leaf binder, the combination 80 with cover members, of a pair of detachable transfer bars normally lying adjacent to the respective cover members and each having impaling posts thereon adapted to extend through the leaves, and means including independently operable locks on the respective cover members for securing the transfer bars thereto.

10. In a loose leaf binder, the combination 90 with cover members having sockets therein, of a pair of detachable perforated transfer bars normally lying adjacent to the respective cover members and each having impaling posts thereon adapted to extend through the leaves, through the perforations of the opposite bar and into the sockets of the opposite cover member, a separate shouldered post also extending through perforations in the transfer bars and into sockets of both cover members to space the said bars apart and independently operable locks on the respective cover members cooperating with the opposite ends of said separate post.

11. In a loose leaf binder, the combination 105 with cover members, of transfer bars detachably associated with said cover members and each provided with impaling posts, and a binding member shouldered to engage said transfer bars, and means for detachably securing said binding member to said cover members.

12. In a loose leaf binder, the combination with cover members of a pair of transfer bars provided with posts and detachably associated with said cover members, and means 115 for detachably connecting said cover members and securing said transfer bars to their respective cover members permitting the detachment therefrom of either cover member and its transfer bar.

13. In a loose leaf binder, the combination with cover members, of transfer bars removably associated therewith and provided with impaling posts, and a binding means for said cover members independently and detachably connected to each cover member and adapted to detachably secure the transfer bars to their respective cover members.

14. In a loose leaf binder, the combination 130 with the cover members, of transfer bars re-

movably associated therewith and provided with impaling posts, and a coupling means for said cover members adapted to independently and detachably secure the transfer bars to their respective cover members.

15. In a loose leaf binder, the combination with cover members, of detachable transfer

bars normally lying adjacent their respective cover members and each having impaling posts thereon, and means for independently 10 securing the transfer bars to their respective cover members.

ERIC C. MOORE.
